UNITED STATES PATENT OFFICE.

HENRY D. MORGAN, OF LIVERPOOL, ENGLAND.

SOAP-FRAME.

SPECIFICATION forming part of Letters Patent No. 594,889, dated December 7, 1897.

Application filed December 30, 1896. Serial No. 617,502. (No model.) Patented in England March 9, 1893, No. 5,107.

To all whom it may concern:

Be it known that I, HENRY DAWSON MORGAN, engineer, a subject of the Queen of Great Britain and Ireland, residing in Kitchen 5 Street, Liverpool, in the county of Lancaster, England, have invented new and useful Improvements in Soap-Cooling Frames, of which the following is a specification.

The invention was patented in England 10 March 9, 1893, numbered 5,107.

This invention has reference to apparatus called "frames" used in the manufacture of soap, into which the hot soap is poured and wherein it is cooled prior to being formed or 15 pressed into the shapes required.

The type of frame to which the invention relates is that wherein the sides, ends, and bottom constitute separate parts so formed and provided with parts that they can be 20 readily put together and fastened up and taken down; and the main object of my invention is to provide frames of a light yet strong construction and the parts of which can be readily put together and taken to 25 pieces and which shall be automatically made tight against leakage when the soap is poured in.

The side and end parts of a frame according to my invention are constructed of thin 30 wrought-metal (preferably steel) plates, while the bottom may also be of iron or steel or other suitable material, as wood, and is provided with grooves or recesses, into which the lower edges of the sides and ends fit, or equivalently formed to receive or be connected to them. The sides at each end are turned inward and at these bends are provided or 35 formed with a flute or equivalent formation, by which a tight joint against leakage of soap 40 is effected and extra or special strength is given the frame to resist bending and becoming deformed when the frame is being taken down or put up (or at other times) or through falling or other action upon it. The plates 45 are so constructed or formed and combined that when connected an even surface is presented to the soap and leakage and waste are prevented, and the flutes or equivalent formations above referred to, when they become 50 filled with soap, constitute a packing at the joints, as stated.

The invention will now be further described

with reference to the accompanying drawings, which show a frame in side elevation in Figure 1 and in end view in Fig. 2. A sectional 55 plan of one end of the frame is shown in Fig. 3.

Referring now to the figures, *a* are the side plates of the frame, and *b* are the end plates, the end plates *b* being held by the side plates 60 by the ends *a'* thereof, which are turned round at right angles and provided with flutes or corrugations *a*², the plates fitting on the inside of these inturned edges. By this construction the spaces within the flutes *a*² become 65 filled with soap when used, and this soap constitutes a packing and prevents the leakage of soap from the frame when freshly filled; also, the parts which hold the end plates *b* in position are rendered strong and 70 capable of withstanding the pressure of the plates *b* outward due to the weight of soap thereon. As regards the other parts of the frame, the side plates *a* are provided with 75 strengthening parts *c*, which are riveted to the plates *a* horizontally. In the example shown these strengthening parts consist of channel or semicylindrical bars, as shown, riveted to *a*; but of course other suitable forms of strengthening bars or means may 80 be provided.

The plates *a* and *b* fit at their lower edges in suitable channels or recesses in the bottom *d* of the frame, which is mounted on wheels in the usual way. The end plates *b* and the 85 side plates *d* are held in position by the hinged cleats *e*, mounted in supports *f*, fixed on the plate *b*. The ends of the cleats are so made as to press the side plates against the end plates when they are moved into their fixing 90 or fastening position.

As regards the strength or weight of metal used, the side plates *a* may be about one-eighth of an inch thick, or about No. 10 Birmingham wire-gage, in a frame of, say, six 95 feet deep. The end plates *b* may be of slightly greater thickness, if desired—say three-sixteenths or one-fourth of an inch. However, the invention is not restricted to these sizes or strengths, those given being merely suitable sizes and strengths for the article.

What is claimed in respect of the invention is—

1. A soap-frame comprising the pairs of

sides *a*, *b*, one pair of said sides having its edges extending beyond and inclosing the edges of the other pair of sides, the said extensions being fluted and forming open channels to hold the soap material, substantially as described.

2. A soap-frame comprising a pair of sides *b*, and a pair of sides *a* extending across and beyond the edges of the sides *b* the said extensions being bent laterally and extending

at a distance from the sides *b* to leave a space between, the edges of the plates *a* being bent inwardly and bearing upon the plates *b* at a distance from the edges thereof.

In testimony whereof I hereunto affix my signature in presence of two witnesses.

HENRY D. MORGAN.
